CHARLES AUGUSTUS WARDEN, OF HEMPHILL, WEST VIRGINIA, ASSIGNOR TO KINGSTON-POCAHONTAS COAL COMPANY, OF NEW YORK, N. Y., A CORPORATION OF WEST VIRGINIA.

COAL-LOADING CONVEYER

Application filed May 25, 1926. Serial No. 111,594.

This invention relates to conveyers and particularly to an apparatus designed to facilitate the transference of loose coal in a mine to the cars in which it is transported from the mine.

In present-day methods of mining coal a so-called "short wall" or "long wall" mining machine is used to undercut the body of coal. The coal is then shot down and rests in a loose mass of fragments against the face of the seam. The handling of this loose coal entails a great deal of labor and expense. Attempts have been made heretofore to provide a conveyer which can be moved into the loose mass of coal to pick it up more or less automatically and convey it to the cars on the mine tracks. The apparatus heretofore devised for this purpose is relatively complicated, cumbersome and expensive. While it is capable of transporting the coal to the cars it is not easily handled and moved from place to place as required.

It is the object of the present invention to provide a simple and satisfactory conveyer which will facilitate the transfer of the coal from the face of the seam to the cars and which can be moved easily as the miners advance in working the seam.

Other objects and advantages of the invention will be apparent as it is better understood by reference to the following specification and accompanying drawing, in which

Fig. 1 is a diagram illustrating the manner in which the conveyer is used;

Fig. 2 is a plan view of the conveyer;

Fig. 3 is a side elevation thereof;

Fig. 4 is an enlarged section on the line 4—4 of Fig. 2;

Fig. 5 is a section on the line 5—5 of Fig. 2;

Fig. 6 is a diagram illustrating the method of moving the conveyer into the body of loose coal; and

Fig. 7 is an end elevation of one of the flights.

Referring to the drawing, 5 indicates a coal seam from the face 6 of which a mass 7 of loose coal has been shot down. A plurality of cars 8 are moved upon the mine tracks 9 in the gallery 10 into proper position to receive the coal. A drag conveyer 11 is placed in the

gallery parallel to the tracks 9 and a transfer conveyer 12 is provided to receive the coal from the drag conveyer 11 and to deliver it to the cars 8 which are advanced intermittently as they are filled. The drag and transfer conveyers may be of any suitable type and form no part of the present invention since they are employed commonly for loading purposes in mines.

The conveyer 13 which is hereinafter described in more detail is arranged parallel to the face 6 and is adapted to be forced by a plurality of jacks 14 which rest against the timbers 15 under the mass 7 of broken coal. The conveyer 13 is designed to pick up the loose coal either automatically or with such additional manual handling as may be necessary and to deliver it to the drag conveyer 11. The latter conveys the coal to the transfer conveyer 12 which delivers it to the cars 8.

The conveyer 13 comprises a plurality of sections 15 which are connected by section splicers 16. The sections include a bottom plate 17 and top plate 18 which are held in spaced relation by angles 19 and 20 secured to a side plate 21 and by an angle 22. The top plate 18 has a sloping face 23 extending to the bottom plate 17 and a plurality of loosening bits 24 are secured at intervals to the wedge-shaped housing formed by the top and bottom plates to facilitate the introduction of the conveyer beneath the body of coal.

A chain 25 is disposed about the sprocket 26 at one end of the conveyer on a shaft 27. The shaft is adjustable by means of screws 28 which are mounted in yokes 29 on the frame of the conveyer and are adapted to adjust the shaft and consequently to take up the slack of the chain. At the other end of the conveyer the chain 25 passes around a sprocket 30 which is mounted on the shaft of a speed reducer 31. A shaft 32 and coupling 33 connect the speed reducer to a motor 34 which supplies the power to drive the conveyer.

A plurality of flights 35 are secured at intervals to the chain 25 and are movable therewith along the top plate 23 of the conveyer toward the sprocket 30. After passing

over the sprocket 30 the flights return with the chain beneath the top plate 23 to the opposite end of the conveyer. The flights are thus adapted to move the coal which falls upon the top plate 18 toward the discharge end of the conveyer. At that end the top plate 23 is inclined upwardly to permit the discharge of the coal upon the drag conveyer 11. The upwardly inclined portion of the top plate is supported by angles 36 secured to the motor base plate 37.

Each of the flights is provided with a U-shaped section 38 adapted to straddle the chain 25. The flights are secured by bolts 15 which pass through the chain. The structure permits the even distribution of the load to the chain.

The operation of the conveyer will be understood readily from the foregoing description. When the coal has been shot down, the conveyer which has been arranged in parallel relation with the face of the seam is moved forwardly by means of the jacks 14 until the loosening bits 24 and the top plate 23 are beneath the loose coal at the front of the mass. The motor is then started and the flights 35 advance along the top plate carrying the coal with it and discharging it upon the drag conveyer 11. The conveyer is moved from time to time toward the face of the seam by operating the jacks 14 until all of the loose coal has been picked up by the conveyer and transferred to the car. The face of the seam is then exposed and the operations of undercutting and of shooting down the coal can be repeated, after which the conveyer is again placed in operation to remove the loose coal.

The structure of the conveyer as herein described is simple and it can be constructed and operated at a relatively low cost. It is efficient in operation and permits the removal of the loose coal rapidly so that the face of the seam is exposed for further operations within a comparatively short time. The parts of the conveyer may be of sturdy construction suitable for the rough usage to which it is subjected. There are few parts and these are not likely to break. If broken 50 the parts can be repaired or replaced easily.

The preferred structure of the conveyer is illustrated and described herein, but various changes can be made in the details of construction and arrangement of the parts without departing from the invention or sacrificing any of the advantages thereof.

I claim:—

1. In a conveyer, the combination of a plate having a longitudinal material receiving portion and a longitudinal loading edge substantially co-extensive with the length of said plate and the loading portion of the conveyer, said loading edge being arranged to be moved under the material to be transported to force the material onto said material re-

ceiving portion of the plate, flights superposed on the material receiving portion of said plate and means connected to the flights and to a source of power to advance the flights longitudinally of the plate to move the material along the material receiving portion of the plate. 70

2. In a conveyer, the combination of a plate having a material supporting and receiving surface and a longitudinal sloping face provided with a longitudinal edge substantially co-extensive with the length of said sloping face, said longitudinal edge being arranged to be moved under the material to be transported to force the material onto the sloping face and onto the material supporting and receiving surface, flights superposed on the material supporting and receiving surface and means connected to the flights and to a source of power to advance the flights longitudinally of the material supporting and receiving surface to move the material therealong. 75

3. In a conveyer, the combination of a plate having a material supporting and receiving surface and a longitudinal sloping face provided with a longitudinal edge substantially co-extensive with the length of said sloping face, said longitudinal edge being arranged to be moved under the material to be transported to force the material onto the sloping face and onto the material supporting and receiving surface, a plurality of loosening bits on the longitudinal edge, flights superposed on the material supporting and receiving surface and means connected to the flights and to a source of power to advance the flights longitudinally of the material supporting and receiving surface to move the material therealong. 80

4. In a conveyer, the combination of a plate having a longitudinal material receiving portion and a longitudinal loading edge substantially co-extensive with the length of said plate, said loading edge being arranged to be moved under the material to be transported to force the material onto said material receiving portion of the plate, a chain running the length of the plate, means for driving the chain in a vertical plane, a plurality of flights superposed on the material receiving portion of the plate secured to the chain and movable thereby along the material receiving portion of the plate. 85

5. In a conveyer, the combination of a plate having a longitudinal material receiving portion and a longitudinal loading edge substantially co-extensive with the length of said plate, said loading edge being arranged to be moved under the material to be transported to force the material onto said material receiving portion of the plate, a plurality of loosening bits on the longitudinal edge of the plate, a chain running the length of the plate, means for driving the chain in a ver- 90

tical plane, a plurality of flights superposed on the material receiving portion of the plate secured to the chain and movable thereby along the material receiving portion of the plate.

6. In a conveyer, the combination of a plate having a material supporting and receiving surface in a substantially horizontal plane and having a longitudinal sloping face provided with a longitudinal loading edge substantially co-extensive with the length of said sloping face, a plurality of loosening bits on said loading edge, a chain superposed on the material receiving surface and movable longitudinally therealong, means for driving the chain in a substantially vertical plane and a plurality of flights secured to the chain and superposed on the material receiving portion of the plate and movable therealong by the chain.

10 7. In a conveyer, the combination of top and bottom plates in spaced relation, the top plate having a longitudinal sloping face forming with the bottom plate a wedge-shaped longitudinal loading edge substantially co-extensive with the length of the sloping face, a chain on said top plate, means for driving the chain in a substantially vertical plane and a plurality of flights secured 25 to the chain superposed on said top plate and movable along the top plate and thereafter through the space between the top and bottom plates.

8. In a conveyer, the combination of top and bottom plates in spaced relation, the top plate having a longitudinal sloping face forming with the bottom plate a wedge-shaped longitudinal loading edge substantially co-extensive with the length of the 30 sloping face, means for moving the edge under the material to be transported, a chain on the top plate, means for driving the chain in a substantially vertical plane and a plurality of flights secured to the chain superposed on said top plate and movable by the chain longitudinally along the top plate and thereafter through the space between the plates.

45 9. In a machine for loading coal in a mine, the combination of a plate having a sloping face and a longitudinal loading edge substantially co-extensive with the length of the sloping face and arranged to be moved under a pile of coal extending parallel to and substantially the length of the pile of coal shot down from the seam in the mine, means for moving the edge of the plate under the coal to be transported, a plurality of flights superposed on said plate and means connected to 50 the flights and to a source of power to advance the flights longitudinally of the plate.

10. In a machine for loading coal in a mine, the combination of top and bottom plates in spaced relation, the top plate having a sloping face forming with the bottom plate a

wedge-shaped longitudinal edge substantially co-extensive with the length of said sloping face, extending parallel to and substantially the length of the pile of coal shot down from the seam in the mine, means for moving the edge of the plate under the coal to be transported, a chain on said top plate, means for driving the chain in a substantially vertical plane and a plurality of flights secured to the chain superposed on said top plate and movable 70 through the space between the plates.

In testimony whereof I affix my signature.

CHARLES AUGUSTUS WARDEN.
